UNITED STATES PATENT OFFICE.

LEWIS Y. MYERS, OF CANTON, OHIO.

HAY-CARRIER.

SPECIFICATION forming part of Letters Patent No. 243,600, dated June 28, 1881.

Application filed February 14, 1881. (No model.)

To all whom it may concern:

Be it known that I, LEWIS Y. MYERS, of Canton, in the State of Ohio, have invented certain new and useful Improvements in Hay-Carriers; and I do hereby declare that the following is a full, clear, and exact description thereof, reference being had to the accompanying drawings, and to the letters of reference marked thereon, which form part of this specification, and in which—

Figure 1 is a side elevation, and Fig. 2 the same with one side broken away to show the slotted hook, &c. Fig. 3 is a detail.

The nature of my invention relates to that class of hay-carriers which run upon a suspended rail and are provided with a latch and stop, by which they are stopped and the fork released at any desired point; and it consists in the peculiar construction and arrangement 20 of the latch, and also in the swivel to which the hoisting-rope is secured, as will be herein-after more fully set forth.

In order to enable others skilled in the art to which my invention appertains to make and use the same, I will now proceed to describe its construction and operation, referring to the accompanying drawings, in which—

A represents a common T-rail, such as is usually used for the carrier to run upon. This 30 rail is suspended in the barn or wherever desired, and upon it travels the frame B of the carrier, suspended by two wheels, b b, at each of its upper corners. The frame B is composed of two sides of metal, having at one of 35 its lower corners a sheave-wheel, c, and at the other a swiveled bar, d, to which the hoisting-rope e is secured, as seen in Fig. 3. The frame B is on its under side, near the center, provided with a cone-shaped guide, D, which is 40 open at both ends, and serves to guide the fork-pulley to the suspending-hook f upon the end of the latch C. The latch C is a metal bar having at one end a hook, f, and being formed at the other end with an upward projection, 45 in which is a notch, g, one side of this notch being longer than the other, as seen in Figs. 1 and 2. The latch is also provided with two L-shaped slots, x x', through which pass two

pins, h h', suspending the latch loosely between the sides of the frame B.

Upon the under side of the rail A, at the desired point of discharge, is placed a stop, i, which engages with the notch g in the latch-bar, as will be hereinafter described.

The hoisting-rope is secured at one end to 55 the swiveled plate or bar d, and passes around the fork-pulley, as seen, thence over the sheave at the opposite end of the frame, and is then led downward to the horse or other motive power.

In operation, when the fork has been secured to its load of hay it is drawn up till the hook or loop on the fork-pulley passes up through the guide D as far as it will go, when the strain upon the rope will draw the carrier along the 65 rail. The latch-bar being in the position shown in Fig. 1—that is, thrown forward on the pins h h'—and the stop inclosed by the notch g, when the carrier starts forward the stop i will catch the rear side of the notch and 70 draw the bar back till its point engages with the fork-pulley, when, from the peculiar shape of the slots, as seen in Fig. 2, the rear end of the bar will drop down, locking it in position, as shown. When the carrier returns the bar 75 or latch will strike the stop i and the rear end be raised and pushed forward, releasing the fork-pulley, and the forward end of the latch drops, in turn, upon the L-shaped slot x' and locks it open. By this means the latch is always held in a locked position, whether open or closed. The pivoting of the bar d prevents the strain of the rope e from twisting the fastening and makes it much better and stronger.

It is obvious that, if desired, the frame may 85 be suspended upon a round iron rod by means of two grooved wheels, instead of the T-rail shown in the drawings.

Having thus fully described my invention, what I claim as new, and desire to secure by 90 Letters Patent, is—

1. In a hay-carrier, a sliding latch-bar formed with a hook upon one end, and provided with L-shaped slots, which adapt it to be locked in position whether closed or open, substantially as and for the purpose set forth.

2. In a hay-carrier, the sliding latch-bar formed with a hook, *f*, upon one end and notch *g* upon the other, and provided with L-shaped slots *x x'*, substantially as and for the purpose herein described.
3. The combination, in a hay-carrier, of the rail *A*, frame *B*, and the fork-pulley with the sliding slotted latch-bar *C* and stop *i*, all constructed and arranged to operate substantially as and for the purpose herein described.

In testimony that I claim the foregoing as my own I affix my signature in presence of two witnesses.

LEWIS Y. MYERS.
